James Jenkinson

UNITED STATES PATENT OFFICE.

JAMES JENKINSON, OF WILLIAMSBURG, NEW YORK, ASSIGNOR TO HIMSELF
AND EMANUEL MANDEL, OF SAME PLACE.

IMPROVEMENT IN TEMPERING STEEL SPRINGS.

Specification forming part of Letters Patent No. 23,142, dated March 1, 1859.

To all whom it may concern:

Be it known that I, JAMES JENKINSON, of Williamsburg, in the county of Kings and State of New York, have invented a new and Improved Method of Tying Coiled Springs, for the Purpose of Hardening and Tempering the Same; and I do hereby declare that the following is a full, clear, and exact description of the same, reference being had to the annexed drawings, making a part of this specification, in which—

Figure 1 represents a front elevation of the apparatus which I employ for coiling and tying the springs. Fig. 2 is a plan or top view of the same, representing the wheel to which the spring is tied and the spring as far as it is coiled in section. Fig. 3 represents the manner in which the spring is arranged after it has been hardened, for the purpose of tempering the same; and Fig. 4 represents a section of a coiled spring tied in the old style.

Similar letters of reference indicate corresponding parts in the several figures.

This invention consists in arranging the several wires which serve for tying the coil in such a manner that one end of the same always lies flat against the under side of the coil, while the other end of the wire is bent over the consecutive rings of the coil and twisted round the straight end, so that the several rings constituting the coil are tied to the straight ends of the wires, and that by nipping each of the wires in one place the straight ends of the same may be removed and the coil placed on the bobbin from which it is unwound, in order to temper the spring, without the necessity of letting one of the rings escape on the floor, whereby the springs always take up some dust and impurities, so that much cleaning is required and much time to gather them up.

To enable others skilled in the art to fully understand and use my method of tying the coils, I will proceed to describe it.

A is a wheel, which is attached to a stand, B, and which rotates freely on an arbor, a. The wheel is of hexagonal form, but it may be made in any other convenient form, and in the center of each side, on its outer edge, pins b are inserted, to which the wires c c' are tied by one end. The spring C is fed to the wheel

A over the conducting-rollers D, and the inner end, d, of the spring is tied to the hub of the wheel A by one of the wires, c', and, as is usually done with smaller kinds of springs, two of them are fed to the wheel at the same time, one being placed on the top of the other, as clearly represented in Fig. 1. The end c* of the wire c', which holds the end d of the spring, runs down behind the hub, and it is turned over the hub and over the end of the spring and drawn through one of the notches e in the edge of the hub, and it is then wound round the wire c', extending from the arm of the wheel down to the hub. The second wire, c, is drawn down under the first ring, g, close to the hub, turned over the springs, as represented at f, and twisted round that part of the wire c lying between the ring g and the arm of the wheel in such a manner that this ring is perfectly confined. The next one of the wires, c, is turned over the ring g in the same manner, and so on to the third, fourth, and fifth wires, when the second ring, g', commences, and this is tied in the same manner to the wire c', and so on to the rest of the wires, by turning the loose end of the wire over the ring of the coil and round that end of the wire which extends from the arm down to the hub, as is clearly represented in Figs. 1 and 2. The old method of tying these coils is represented in Fig. 4, where both ends of the wires h h are loose and turned over the several rings as they follow each other in opposite directions. After the coil is finished, the inner end, d, of the same is untied from the hub of the wheel A, and the coil is hardened in the usual manner, and each of the wires c c' is now nipped at the under side of the coil, so that the straight ends of the wires, which are loosened from the pins b, may be removed without difficulty, and if the coil be now placed on a bobbin, F, as represented in Fig. 3, and after the pieces of wire on the upper side of the coil have been removed, which can be done quite easily after the straight ends of the same have been drawn out, the coil is ready for tempering. When the coil is tied after the old plan, (represented in Fig. 4,) it is necessary to nip the wires at each ring of the coil and on both sides of the same, and by the time the wires are all removed the coil becomes loose and drops

on the ground, where it takes up some dust and other impurities, which causes great inconvenience, and at the same time it is not only troublesome to gather up the springs again ready for tempering, but they also get broken very easily during this operation.

Having thus described my invention, what I claim as new, and desire to secure by Letters Patent, is—

Arranging the wires $c c'$ in such a manner

that by tying one end of each of the same to one of the arms of the wheel on which the coil is formed, and by extending the ends so tied down to the hub of the wheel, the loose ends of the wire serve to fasten the several rings of the coil, substantially as described.

JAMES JENKINSON.
